UNITED STATES PATENT OFFICE

RALPH HUDSON PERSHALL, OF BREMERTON, WASHINGTON, ASSIGNOR TO SANICUT MANUFACTURING COMPANY, OF BREMERTON, WASHINGTON, A CORPORATION OF WASHINGTON

DISPENSER OF VARIOUS SUBSTANCES, SUCH AS LIQUIDS, POWDERS, GRANULATES

Application filed October 14, 1930. Serial No. 488,568.

This invention relates to improvements in dispensing devices for dispensing molasses, sugar, cream, and the like.

The device in brief consists of a closure for 5 receptacles provided with a spout for dispensing the various substances and means to slidably cover and uncover the nozzle.

The main object of the invention is to provide a leak-proof dispensing device which 10 is sanitary and simple in construction.

Another object of the invention is to provide a device of this kind for dispensing liquids or solids arranged so that the amount of substances dispensed can accurately be 15 measured off.

Other objects of the invention will appear as the disclosure progresses. The drawing is intended to merely indicate a possible embodiment of the invention. It is obvious 20 that the actual needs of manufacture may necessitate certain mechanical changes. It is therefore not intended to limit the invention to the embodiment illustrated but rather to define such limits in the appended claims.

25 For a more general understanding of the invention attention is called to the drawing. In this drawing like reference characters denote like parts throughout the specification.

Figure 1 is a top view of the dispensing 30 device.

Figure 2 is a section on line 2—2 of Figure 1.

Figure 3 is a section on line 3—3 of Figure 1, and

35 Figure 4 is a rear view of the device.

Referring now to the drawing in detail, numeral 1 designates the body of the dispensing device formed round in section to fit the top of a bottle or can. The front of 40 the body is provided with a spout 2 and in the top thereof is an outlet opening 3. At two sides of the outlet opening are outwardly bent flanges 4 and 5 which slidably co-operate with the inwardly bent flanges 6 and 7 of 45 the cover 8.

The cover is made of a flat sheet of material, tapered at the front to fit the contour of the spout and provided with a downwardly bent end 9 which fits in a slot 10 of the operating handle 11. The operating handle com-

prises a flat top 12, side walls 13 and a front wall 14 and is pivoted to a bracket 15 attached to the rear of the body 1 by the rivets 16. The pivoting element consists of a bolt 17 passing through the side walls of the bracket 15 and the side walls 13 of the operating handle. Placed around the bolt 17 is a torsion spring 18 for normally urging the operating lever to the left.

To open the spout the operating lever is 60 pushed down as shown in dotted lines in Figure 2. This action will pull the cover 8 to the right and uncover the spout 2 for pouring out the contents of the receptacle. When the handle is released the cover 8 due to the action of the torsion spring will move to the left and cover up the spout.

As noted in Figure 2 the front wall 14 and side walls 13 of the operating handle extends 70 below the lower rim of the body 1 and forms a stop 19 which bears against the rear of the body when the operating handle is fully pressed down.

It will thus be seen that I have provided a 75 simple, efficient and sanitary closure for receptacles. The slidable cover will always keep the opening closed when through pouring due to the action of the torsion spring making it impossible for flies, insects or dust to get into the container.

Having described my invention, I claim

1. In a device of the class described, the combination of a body member having an opening at the top, of a spout at the front thereof, a slidable cover above said opening, said cover having downwardly bent rear end, an operating handle having a slot in the top face, said downwardly bent end fitting into said slot, a bracket attached to said body member and pivotally supporting said operating handle, a torsion spring for normally keeping the top of said operating handle on a substantially horizontal plane, and a stop at the lowermost edge of said handle for limiting the downward swing of said handle.

2. In a device of the class described, the combination of a body member having an opening at the top, of a spout at the front thereof, a slidable cover above said opening, said cover having a downwardly bent rear end,

an operating handle having a slot in the top face, said downwardly bent end fitting into said slot, a bracket attached to said body member and pivotally supporting said operating handle, a torsion spring for normally keeping the top of said operating handle on a substantially horizontal plane, said operating handle including a front wall and two side walls, said side walls extending below the lower edge of said body portion and forming a stop to limit the downward movement of said operating handle.

RALPH HUDSON PERSHALL.
